UNITED STATES PATENT OFFICE.

GEORGE F. LEONARD, OF FAIRMONT, WEST VIRGINIA.

TWIST-DRILL AND SOCKET.

SPECIFICATION forming part of Letters Patent No. 611,494, dated September 27, 1898.

Application filed April 30, 1898. Serial No. 679,341. (No model.)

To all whom it may concern:

Be it known that I, GEORGE F. LEONARD, a citizen of the United States, residing at Fairmont, in the county of Marion and State of West Virginia, have invented new and useful Improvements in Twist-Drills and Sockets, of which the following is a specification.

This invention relates to improvements in twist-drills and sockets. As ordinarily constructed the drill-shank terminates in a flat tang, which enters a transverse slot in the socket for holding the drill from turning. Such holding means being at the extremity of the shank, also at its smallest diameter, is frequently not sufficiently strong to withstand the strain, with the result that the tang either twists entirely off or the socket-slot reams out and permits the drill to turn. Various means have been proposed for remedying these defects, but they have proven deficient on account of weakness, liability to disorder, projection of parts preventing the socket from running close to the work, &c.

The object of the present invention is to overcome the difficulties noted by forming the parts with flat or other engaging or holding surfaces entirely within the socket and of sufficient extent to preclude possibility of twisting.

The invention consists in the novel features of construction hereinafter fully described and claimed, and illustrated by the accompanying drawings, in which—

Figure 1 is an elevation, partly in section, of a socket and upper portion of a drill of my improved form. Fig. 2 is a cross-section on line $y-y$ of Fig. 1. Fig. 3 is an elevation of the socket, and Fig. 4 a detail view of the shank end of a drill.

Socket A is formed with the usual tapering bore A' to receive tapering drill-shank B, the extremity of the latter forming tang C, which enters transverse slot D in the socket, and it is to reinforcing this connection that the present invention is directed. To this end socket

A is formed on one side of its axial line with transverse vertically-elongated slot E, partially coincident with bore A', and fixed therein is key F. The extremities of this key con-

form to the exterior contour of the socket, as clearly shown in Fig. 2, so that there is

no projection to interfere with running the socket close to the work.

Drill-shank B is flattened at G, from its extremity downward, to pass key F and to flatly engage the same when positioned. Tang C is thus almost entirely relieved of strain, and the hold of the socket upon the drill is such that it is impossible for the drill to twist or work loose. Neither the strength of the drill nor its use in sockets of ordinary form are impaired by the flat on its shank. The drill is held absolutely true, as the shank-flat occurs entirely within the socket, the end of the latter being closed by a circular or unbroken section of the shank.

I do not limit myself to flat engaging or locking surfaces on the drill and socket, and it will be understood that the improvement is applicable to other tools and sockets or chucks than those here described and shown.

The improvement is simple and inexpensive and drills and sockets now in use may be readily conformed thereto.

It will be observed that the usual external contour of the socket is preserved, and that the same is not encumbered with set-screws and other projecting and movable parts, and that the socket is constantly ready to receive or discharge the drill.

Having thus fully described my invention, what I claim, and desire to secure by Letters Patent, is—

1. The combination with a socket having a bore circular in cross-section, the socket being formed with a transverse slot intermediate the ends of the circular bore, one side of the slot being coincident with the bore, and a key fixed in the slot and having a flat surface which interrupts the circular contour of the bore, of a drill having a circular shank formed with a longitudinal flat extending to a point beneath the flat transverse key when in position in the socket-bore, substantially as shown and described.

2. The combination with a socket having a circular longitudinal bore terminating in transverse slot D having flat sides, the socket being formed beneath slot D with transverse slot E at one side of the longitudinal center of the socket but coincident with one side of the socket-bore, and key F secured in slot E,

of the drill having tang C at the extremity of its shank to enter slot D, the drill-shank being flattened downward from its extremity on one side to pass key F, but flatly engage 5 the same so as to relieve the drill-shank and tang C thereof of torsional strain, substantially as shown and described.

In testimony whereof I have hereunto set my hand in presence of two subscribing witnesses.

GEORGE F. LEONARD.
